UNITED STATES PATENT OFFICE.

DAVID THOMAS KENNEY, OF NORTH PLAINFIELD, NEW JERSEY, ASSIGNOR TO VACUUM CLEANER COMPANY, OF NORTH PLAINFIELD, NEW JERSEY, A CORPORATION OF NEW JERSEY.

SEPARATOR FOR APPARATUS FOR REMOVING DUST.

No. 841,984.

Specification of Letters Patent.

Patented Jan. 22, 1907.

Application filed May 28, 1905. Serial No. 262,812.

To all whom it may concern:

Be it known that I, DAVID THOMAS KENNEY, a citizen of the United States of America, and a resident of the borough of North Plainfield, county of Somerset, and State of New Jersey, have invented certain new and useful Improvements in Separators for Apparatus for Removing Dust, of which the following is a specification.

This invention is an improvement in the separator disclosed in Letters Patent of the United States No. 739,263, granted to me September 15, 1903, and is intended especially, but not necessarily, to be used in connection with dust-removing apparatus similar to that set forth in the above-mentioned Letters Patent.

The object of the invention is to provide a separator of compact form in which the dust is removed in an efficient and reliable manner and which will remove the finer particles of dust so completely that the air after passing through the separator may be permitted to pass directly through the valves and into the cylinder of a suction-pump without danger of causing material injury or undue wear to the pumping apparatus.

The separator is so organized that it will remove and store within it a considerable amount of dust and require opening, clearing of the strainer, and emptying only at long intervals. The separator is also arranged so that the strainer can be quickly and efficiently cleared.

In the accompanying two sheets of drawings, which form a part of this application, Figure 1 is a vertical section on the line I I of Fig. 2 through a separator embodying my invention. Fig. 2 is a top view of the separator.

The separator, as illustrated, consists of a cylindrical casing or shell 1, which may be supported by means of a flange 2 over a floor-opening or in any suitable manner. The upper rim of the casing is riveted to an annular top plate 3, and to this is secured a removable top plate 4 by means of buttons 5, through which screws 6 pass and are clamped by wing-nuts 7. A throat 8 with a downwardly-opening mouth lies within the upper part of the casing of the separator and is attached to the removable top plate. In order to reduce weight in this removable top plate, it is pref-

erably only large enough to cover that part of the casing which lies within the throat and lap the annular top plate which covers the casing exterior to the throat. An inverted bag 9 of filter-cloth, which for strength is preferably of globular form when distended, forms a cloth strainer of considerable area and lies within the throat and across the mouth of the throat. The open end of the strainer-bag is connected to the periphery of the throat, preferably by being lapped over an outwardly-turned flange 10 around the downwardly-opening mouth of the throat, and is conveniently secured by drawing a string through a hem at the mouth of the bag and tying. The bag is held within the throat by a coil-spring 11, which is suspended from a hook projecting from the under side of a plug 12, which is screwed in the top plate. This suspension for the bag is therefore readily removable, for by unscrewing the plug the spring can be detached and the strainer-bag released without otherwise opening or taking apart the separator, so that the bag can be turned inside out and be cleaned.

As illustrated, the throat is wholly within the casing of the separator and is of smaller diameter, so that an annular space is formed between the exterior walls of the throat and the casing, which is opened at the bottom and closed at the top by the annular top plate. The bottom of the casing tapers downwardly and is provided with a trap-door 13, which is opened to remove accumulated dust. A cord 14 hangs from the bottom of the strainer-bag within reach at the opening in the bottom of the casing, where it can be seized and jerked to agitate the strainer-bag and shake the dust therefrom. The separator is provided with a tangentially-directed inlet 15, which opens into the annular space between the throat and casing. An outlet 16 leads from the throat-chamber through the top plate.

In using the separator a partial vacuum is created in the throat by a pump which is connected to the outlet, and dust-removing apparatus is connected by pipes to the inlet. The dust-laden air enters the casing near the top in a tangential direction, encircles the casing in a spiral course downwardly in the annular chamber with arrested velocity, and while passing through this portion of the

separator the heavier dust-particles settle out of the air and fall to the bottom of the separator. The air-current is thence upwardly through the mouth of the throat and 5 into the throat and through the strainer-bag, which will be distended by the air-pressure, as illustrated, and the finer particles of dust separated from the air as it passes therethrough. This strainer-bag may, if desired, 10 to be stiffened by bands 17.

What I claim as new, and desire to secure by Letters Patent of the United States, is—

1. A separator for dust-removing apparatus, consisting of a casing, a downwardly 15 opening throat within the casing forming an annular chamber between the exterior walls of the throat and the casing, a strainer-bag through which the air to be purified passes located within the throat, having its edge 20 connected to the peripheral wall of the throat, an inlet connecting to the annular chamber, and an outlet from the throat, substantially as described.

2. A separator for dust-removing apparatus, consisting of a casing, a throat downwardly opening into the casing, a cloth strainer-bag through which the air to be purified passes located within the throat having its edge connected to the peripheral 30 wall of the throat, a suspension for the strainer-bag, and means for agitating the strainer-bag, substantially as described.

3. A separator for dust-removing apparatus, consisting of a casing, a throat downwardly opening into the casing, a cloth strainer-bag through which the air to be purified passes located within the throat having its edge connected to the peripheral wall of the throat, and a removable suspension for the strainer-bag, substantially as described.

4. A separator for dust-removing apparatus, consisting of a casing, a downwardly opening throat within the casing forming an annular chamber between the exterior wall 45 of the throat and the casing, a cloth strainer-bag through which the air to be purified passes located within the casing having its edge connected to the lower edge of the peripheral wall of the throat, an elastic suspension 50 for the strainer-bag, and means for agitating the strainer-bag, substantially as described.

5. A separator for dust-removing apparatus, consisting of a casing with an annular top plate, a throat downwardly opening within the casing forming a downwardly-opening annular chamber below the annular top plate and between the exterior walls of the throat and the casing, a removable top plate 60 from which the throat is suspended, an inlet connecting to the annular chamber, and an outlet from the throat, substantially as described.

6. A separator for dust-removing apparatus, consisting of a casing, a downwardly-opening throat within the casing forming an annular chamber between the throat and casing, a strainer-bag through which the air to be purified passes located within the casing having its edge connected to the lower edge of the peripheral wall of the throat, an inlet connected to the annular chamber, and an outlet from the throat above the point of attachment of the strainer-bag to the throat. 75

7. A separator for dust-removing apparatus, consisting of a casing with an annular top plate, a removable top plate fitting upon the annular top plate, a throat closed at its upper end by the removable plate and extending downwardly within the casing with a lower open end and forming an annular chamber between its side walls and the walls of the casing, a strainer-bag supported by the throat, an inlet connected to the annular casing and an outlet in the removable top plate connected to the throat. 80

8. A separator for dust-removing apparatus, consisting of a casing, a downwardly-opening throat within the casing forming an annular chamber between the throat and casing, an inverted strainer-bag through which the air to be purified passes located within the casing, having the edge of its mouth connected to the lower edge of the peripheral wall of the throat, an inlet connected to the annular chamber and an outlet from the throat above the point of attachment of the strainer-bag to the throat. 95

Signed by me at New York city, borough of Manhattan, New York, this 25th day of May, 1905.

DAVID THOMAS KENNEY.
